UNITED STATES PATENT OFFICE

155,946

DESIGN FOR A JEWELRY BOX OR THE LIKE

Bernard Ulvad, Leominster, Mass., assignor to Foster Grant Co., Inc., Leominster, Mass., a corporation of Massachusetts

Application November 30, 1948, Serial No. 149,873

Term of patent 14 years

(Cl. D86—9)

To all whom it may concern:

Be it known that I, Bernard Ulvad, a citizen of the United States, residing at Leominster, Worcester County, State of Massachusetts, have invented a new, original, and ornamental Design for a Jewelry Box or the like, of which the following is a specification, reference being had to the accompanying drawings, forming part thereof, in which:

Fig. 2 is an end elevation, with the lid and container separated;

Fig. 3 is a top plan view of the container with the lid removed;

Fig. 4 is a bottom plan view of the container;

Fig. 5 is a top face view of the lid; and,
 Fig. 6 is a rear face view of the lid.

I claim:

The ornamental design for a jewelry box or the like, substantially as shown.

BERNARD ULVAD.
